WEIGHING SCALE

Grant M. Richard, Toledo, Ohio, assignor to
Toledo Scale Company, Toledo, Ohio, a corpora-
tion of New Jersey

Application May 11, 1938, Serial No. 207,240

5 Claims. (Cl. 308—2)

This invention relates generally to weighing scales, and more particularly to "mechanically set" pivots in the levers of such weighing scales.

The operation of mechanically inserting pivots in scale levers of the type referred to by machining a taper on a portion of the pivot and driving it into a taper reamed hole in the lever is well known, it being described in detail in U. S. Patent 1,459,449 to H. O. Hem. Such tapered pivot construction when correctly fitted results in a very firmly seated pivot but it is expensive; the proper diameter must be determined by frequently fitting the tapered pivot since a hole that is a few thousandths of an inch too large

15 may spoil the entire lever.

The object of the present invention is the provision of improved, inexpensive means for mechanically setting pivots in levers.

A further object is the provision of a scale 20 pivot having a cylindrical body portion adapted to be inserted into a reamed hole having parallel sides.

Another object is the provision of improved 25 key locking means adapted to be inserted into a groove in the pivot body and to cut its own seat in the body of the lever.

These, and other objects and advantages will 30 be apparent from the following description in which reference is had to the accompanying drawing, illustrating a preferred embodiment of the invention and in which similar reference numerals refer to similar parts throughout the several views.

In the drawing:

35 Fig. I is a perspective view of the end of a lever equipped according to the invention.

Fig. II is an enlarged fragmentary view of the locking means sectioned substantially along the line II—II of Figure III.

40 Fig. III is an enlarged fragmentary end view of the locking means showing the end contour of the key in greater detail; and,

Fig. IV is a perspective fragmentary view of a modified form of pivot.

45 Referring to the drawing in detail, and particularly to the form shown in Figures I to III inclusive, the pivot 11, according to the invention, comprises a substantially cylindrical body 12 having portions 13 and 14 adjacent its ends, 50 which are machined to form knife edges 15 for engagement with the usual hardened scale bearings (not shown). For the purpose of locking the pivot 11 in a lever 16 a longitudinally extending rectangular slot 17 is milled into the cylindrical body of the pivot 11. This slot 17 is radially

spaced from a plane passing vertically through the knife edge 15 and is adapted to receive a key 18. This key 18 is longitudinally tapered and the tapered face is V milled forming sharp cutting edges 19. The key is preferably made from steel and hardened. The lever 16 is provided with a plurality of bores 20, in spaced relation to each other in a manner well known. When the pivot 11 is positioned in one of the bores 20, and its knife edge 15 is properly located, the 10 key 18 is inserted into the slot 17 and driven inwardly so that the sharp edges 19 cut into the softer metal of the lever body and firmly lock the pivot against rotation. The metal displaced by the edges 19 mostly moves into the V groove. 15 The wedging effect, which is caused when the key 18 is driven against its taper, securely holds the pivot against longitudinal displacement. In some installations, especially in scales of higher capacities, it may be desirable to drive a similar 20 key 18 into the lever bore from the opposite side.

In scales having very high capacity it is occasionally desirable, for the sake of economy, to make the body 12a of the pivot 11a from a comparatively inexpensive low carbon steel and drive 25 hardened knife edge portions 15a, made from high grade steel, into slots 21 cut into the pivot body for this purpose. This modified form of pivot, as shown in Figure IV, is securely locked into the lever 16a in a similar manner by keys 30 18a.

From the foregoing description it will be appreciated that among others the objects of the invention as specifically aforesaid are achieved. It is to be understood, however, that the invention 35 is susceptible to variations, modification and change within the spirit and scope of the subjoined claims.

Having described the invention, I claim:

1. In a weighing scale, in combination, a lever, 40 a supporting pivot seated in a cylindrical bore in said lever, said pivot comprising a cylindrical body portion, milled portions adjacent each end of said body portion forming pivot edges, there being a substantially rectangular slot in said 45 body portion extending substantially parallel to a plane passing through said knife edges, and a key seated in said rectangular slot for locking said pivot in said lever, said key being substantially rectangular in cross section, one of its sides being 50 tapered in respect to the opposite side and said tapering side being V milled to form a plurality of sharp edges, said sharp edges cutting into the body of said lever.

2. In a device of the class described, in combi- 55

nation, a lever having a smooth cylindrical bore, a pivot retainer having a cylindrical body portion received in said bore and a knife-edge portion extending from said cylindrical body portion, said 5 cylindrical body portion having a key groove extending parallel to its axis, and a key seated in said groove and having a pair of cutting edges to cut a seat along said smooth cylindrical bore in said lever, said key having a space between 10 said cutting edges to receive metal displaced by them in cutting a seat in said lever.

3. In a device of the class described, in combination, a lever having a smooth cylindrical bore, a pivot having a smooth cylindrical body portion fitting within said bore and a knife-edge extending 15 from said body portion, said smooth cylindrical body portion being adapted for preliminary rotational and longitudinal adjustment within said bore to properly position said knife-edge, 20 said cylindrical body portion having a keyway therein and a tapered key having a cutting edge driven into said keyway and cutting its own seat along said bore and fixing said body portion within said bore in a selected position of rotational 25 and longitudinal adjustment.

4. In a device of the class described, in combination, a lever having a smooth cylindrical bore, a pivot having a smooth cylindrical body portion and a knife-edge extending from said body por-

tion, said smooth cylindrical body portion fitting within said bore and being adapted for rotational and longitudinal adjustment therein to properly position said knife-edge, said cylindrical body portion having a keyway therein and a key having parallel sides and a V-groove therebetween whereby cutting edges are formed along said parallel sides, said key being driven into said keyway and cutting its own seat along said bore and serving to fix said pivot to said lever with said 10 knife-edge in adjusted position.

5. In a device of the class described, in combination, a lever having a smooth cylindrical bore extending therethrough, a pivot having a cylindrical body portion and knife-edges extending 15 from each end of said cylindrical body portion, said cylindrical body portion fitting within said bore and being adapted for preliminary rotational and longitudinal adjustment therein to properly position said knife-edges, said cylindrical 20 body portion having key receiving ways extending parallel to its axis, and a pair of keys having cutting edges, said keys being driven along said ways into each end of said bore and cutting 25 their own seats along said bore to fix said pivot to said lever with said knife-edges in adjusted positions.

GRANT M. RICHARD.
